ATTRITION MILL

Filed April 2, 1929

INVENTOR:
August Schückhardt
BY David E. Carlsen
ATTORNEY.

UNITED STATES PATENT OFFICE

AUGUST SCHUCHARDT, OF WINONA, MINNESOTA

ATTRITION MILL

Application filed April 2, 1929. Serial No. 351,887.

My invention relates to grinding mills or devices also known as attrition mills of the type in which the grinding process takes place between two vertically mounted rotatable grinding elements also known as runner heads placed in predetermined parallel, close relation and rotated by separate power units. One of these runner heads is provided with openings about its hub for the material to be ground to pass through and between the said grinding elements. My improvement consists mainly of a new and useful construction for facilitating the feeding materials into the grinding area and also improved mounting means eliminating the chatter or rattling of the said open runner head as hitherto made, said improvements being hereinafter fully set forth and illustrated in the accompanying drawing, in which,—

Fig. 1 is a front elevation of a grinding mill of the type in which my improvements are applicable, the central part of said mill being shown in approximately central vertical section to disclose the improved parts.

Fig. 2 is an enlarged view of the central part of Fig. 1 showing certain modifications.

Fig. 3 is an end view of my improved seal ring and Fig. 4 is an elevation of the hand hole plate used with my device.

Referring to the drawing by reference numerals, 5 and 6 designate respectively left and right pedestals mounted in alignment and on each is mounted a motor of which 7 is the left and 8 the right motor having extended respective drive shafts 9 and 10 in alignment and their adjacent ends close together within in the grinder housing 11.

Said housing has a bearing 11B for shaft 10 and inwardly of this housing the said shaft 10 carries a circular grinding element or disc 12 hereinafter referred to also as the closed runner head. 13 is the other grinding element also referred to as the open runner head and mounted on the end of shaft 9 adjacent to the end of shaft 10 and within housing 11, the grinding process, of course, taking place between these two heads when they are rotated by their respective motors. The outlet means for ground material is not shown or included as a part of my invention,

my improvements being wholly in the means for efficiently feeding material to and through the open runner-head 13 and in a more efficient mounting of the shaft 9 at said open runner-head.

14 is a receiving hopper mounted above and to one side of housing 11 and opening into a housing 15, having suitable rotary means driven by a rotating shaft 16 internally for even feeding of material downwardly to a downwardly directed flue 17 comprising the upper portion of a feeder pedestal P suitably mounted on base 5. This pedestal has a vertical circular opening (designated P² in Fig. 1) in spaced parallel relation to the open runner head 13. Opposite said opening the pedestal is formed as P⁴ in conic-shape directed horizontally toward head 13 and bored centrally for a removable bearing 18 (shown as a ball bearing). Obviously this bearing is thus located as close as possible to the said head 13 and provides a bearing for shaft 9 in a location close to head 13 which is thus held in rotatable but rigid position, a desired condition for same.

19 is a metal head seal ring concentric of and affixed to the rear side of head 13 (as shown in Figs. 1 and 2), said ring being of approximately L-shape in cross section with the base flange inwardly. 20 is a male seal ring with a circular flange 20F arranged to be fixed in concentric relation to and within the base of the ring 19. Rearward from said flange this ring is flared outwardly and terminates in a circular outside face arranged to fit within the bore P² of the feeder pedestal (as in Fig. 1). In the modified form of this male seal ring its large end comprises a circular curved edge, as at 20E in Fig. 2 and the opening P² of the pedestal is correspondingly grooved, as P³ (Fig. 2) for frictional retention of said outer part of the ring. Either type of this ring may be held positively concentric of the female ring 13 by means of a number of radial lugs 20L bored for cap-screws or bolts 21 (Fig. 1) arranged to engage threaded adjacent parts of housing 11. The male ring wall flared outwardly as shown and just described, provides an angular guiding means between which and the adjacent

tapered pedestal bearing P^4 an inclined passage P^5 is formed, leading from flue 17 and opening directly against the inner side of head 13 and its apertures 13A. Said latter apertures extend radially from the hub of member 13 and their outer parts flared outwardly toward the head 12 as clearly illustrated. Thus will be readily seen that the inclined passage P^5 delivers material to be ground directly to and through the head 13 and its apertures 13A through which the material is aided by centrifugal force and momentum to the grinding elements.

Some material not caught in this feeding action may drop down below the cone P^4 but this may be obviated by use of horizontal fixed plates at each side of the cone (not shown). Such material may be readily reached or any lower interior parts in the pedestal made accessible by a hand hole plate 22 shaped in arcuate form as shown in Fig. 4 to normally close the lower rear part of the pedestal below its conic hub member P^4 .

I have not illustrated any means for adjustment of the runner-heads, said means being of well known construction and not constituting a part of this invention. For purpose of brevity and a readier understanding of the device the runner-heads 12 and 13 may also be termed simply as milling heads. The housing 11 of course is readily understood as to construction having a large aperture 11A concentric of and corresponding to the opening P^2 in the feeder pedestal.

I claim:

1. In a mill of the class described having a pair of upright milling heads rotatable in proximity to each other, each mounted on a rotary shaft and said shaft in alinement a plurality of bearings supporting said shaft, a housing about said heads and a feeder pedestal adjoining said housing with an intake hopper in its upper part at an elevation above the milling heads; a female seal-ring fixed concentrically on one of said milling heads nearest the feeder pedestal and of L-shape in cross section and providing a circular collar, said head provided with a circular row of apertures flared out toward the other head, said feeder pedestal provided with a vertical intake flue communicating with said hopper and inclined guide passage means leading downwardly direct from said flue to the adjacent or outer side of the said apertured milling head, said inclined guide means comprises in the pedestal an integral horizontal hub formed with conic exterior tapering toward and terminating at the hub of said open milling head, said conical hub bored centrally for the shaft supporting said milling head and bearing means provided for said shaft within said bore and in proximity to the milling head, and further guide means in approximately parallel relation to said conic face of the hub, comprising a removably

fixed made seal ring with a circular flange retained concentric within the seal ring of the open milling head, the major part of said male ring comprising a circular body flared outwardly from said flange toward the feeder pedestal, said latter pedestal provided with a circular aperture concentric of said milling head and said male seal ring to retain the outer edge of its flared body.

2. The structure specified in claim 1, said outer edge of the male seal ring being rounded, said apertured part of the pedestal formed with a seat for frictionally retaining said outer edge of the male ring.

In testimony whereof I affix my signature.

AUGUST SCHUCHARDT.
